UNITED STATES PATENT OFFICE.

JAMES G. BROWN, OF MILWAUKEE, WISCONSIN, ASSIGNOR TO THE WESTERN STOVE AND MANUFACTURING COMPANY, OF WISCONSIN.

DESIGN FOR A TANK-SHIELD.

SPECIFICATION forming part of Design No. 25,921, dated August 11, 1896.

Application filed February 12, 1896. Serial No. 579,108. Term of patent 7 years.

To all whom it may concern:

Be it known that I, JAMES G. BROWN, of Milwaukee, in the county of Milwaukee and State of Wisconsin, have invented and produced a new and original Design for Tank-Shields for Oil-Stoves; and I do hereby declare that the following is a full, clear, and exact description of the invention, which will enable others skilled in the art to which it pertains to make and use the same, reference being had to the accompanying drawing, and to the letters and numerals of reference marked thereon, which form a part of this specification.

15 The drawing is a perspective view of an oil-tank shield, illustrating my design.

The leading feature of my design is an open scrollwork ornament or frame for strengthening the shield and attaching it to a stove-top.

20 A designates the shield, which is curved to correspond approximately with the shape of an oil tank or reservoir.

C is an ornamental frame constituting the main feature of my design. This frame consists of an upright 1, to which the rear vertical edge of the shield A is attached; a horizontal base 2, joined at a point between its ends to the lower end of said upright and

adapted to rest upon the stove-top; a bracket 3, joined to the front end of the base overhanging the stove-top and adapted to bear against the end flange or margin of said stove-top; an open-work scroll ornament 4, springing from the front side of the upright 1 and joined at intervals thereto and to the forwardly-extending portion of the base, and a smaller scroll ornament 5 in the angle between said upright 1 and the rearwardly-projecting portion of the base 2.

In front of the upright 1 the base 2 is curved to correspond with the curvature of the lower edge of shield A, which rests thereon and is secured thereto, and the rearwardly-projecting portion of the base is curved in the reverse direction, as shown.

45 I claim—

The design for a tank-shield for oil-stoves substantially as shown and described.

In testimony that I claim the foregoing as my own I affix my signature in presence of 50 two witnesses.

JAMES G. BROWN.

Witnesses:

CHAS. L. GOSS,
M. L. EMERY.
